United States Patent Office.

HORACE TARBOX, OF WARWICK, RHODE ISLAND.

Letters Patent No. 83,673, dated November 3, 1868.

IMPROVED AUTOMATIC CAR-COUPLING.

The Schedule referred to in these Letters Patent and making part of the same.

To all whom it may concern:

Be it known that I, HORACE TARBOX, of the town of Warwick, in the county of Kent, and State of Rhode Island, have invented a new and useful Improvement in a Self-Acting Car-Coupling; and I do hereby declare that the following is a full, clear, and exact description of the same, reference being had to the annexed drawings, making a part of this specification, in which—

Figure 1 is a perspective view of an ordinary car-coupling, with my improvement attached.

Figure 2 is a perspective view of the interior.

Figures 3 and 4 are parts of same.

In the accompanying drawing,

A, fig. 1, is a box, attached or cast to a common car-coupling.

Inside of box A is a shaft, b, as represented on fig. 2. This shaft is secured in its place by set-screws, one at each end, holding it on centres, and so it can be turned.

A coil-spring, c, is fastened to one of its ends.

d, figs. 2 and 4, is a lever. One end is fastened to shaft b, the opposite end of which is fitted into a slot in the coupling-pin.

Fig. 3 represents the form of coupling-pin used by me. It is provided with a stop or guide-plate, e, the lower edge of which holds the connecting-link flat; and in position to connect two cars together, as shown on fig. 1.

f, figs. 2 and 4, is a piece of wire, bent the form of a staple, and arranged in slides, so one end or short arm rests against the coupling-pin. The opposite end, or longer arm is carried through the front of box A, as shown in fig. 1.

i, fig. 2, is a lever, made to press against the bend

of wire f, by means of a coil-spring connected to its lower end.

The stop or guide-plate e, fig. 4, is made with a notch or projection on its face, for the purpose of setting or holding the coupling-pin up when required to act.

To use my invention, the coupling-pin is drawn up by the ring on its top, until the end or short arm of wire f is sprung into the notch on plate e by the pressure from lever i. In this position, the lever d is raised, as represented in fig. 4, causing the shaft b to turn, and winding or straining-up spring c.

When attached on a car, the coupling-pin being set, and the two cars brought together, the connecting-link passes into the coupling, the longer arm of wire f is acted on and pressed into box A, drawing the end of short arm from the notch on guide-plate e, and the spring c acting on the lever d, drops the coupling-pin to its place, thus securing the two cars together.

The advantages are, it can be set to couple or not, as desired, and it can be made to fit any coupling now in use, saving the expense of making an entire new coupling.

I do not claim a coupling as my invention; but What I do claim, and desire to secure by Letters Patent of the United States, is—

A car-coupling, composed of the box A, with a shaft, b, and spring c, which has a lever, d, connected to the slotted coupling-pin, with a guide-plate, e, when combined with a projecting staple, f, and lever i, all constructed and operated substantially as described, and for the purpose specified.

HORACE TARBOX.
